WEATHERPROOFING DEVICE

Joseph F. Fauner, Irvington, N. J.

Application October 2, 1933, Serial No. 691,770

15 Claims. (Cl. 20—66)

This invention relates to weather-proofing devices, such as described in my copending application Serial No. 676,397 filed by me June 17, 1933, of which the present case is a continuation in part.

The prime object of this invention is to provide an automatically operable weatherproofing device for doors, windows or similar closures, which will not only form a positive barrier to external elements such as rain and wind, but will at the same time provide means for shedding, catching and conveying moisture from within the device, when the door or window is closed, and which will form an unobtrusive threshold or sill, when the door or window is open.

Another object of this invention is to construct such device from extruded, continuous material having pre-determined cross-sections, adapted to include all essential features requisite to perfect weather-proofing means for doors or windows.

Another object of this invention is to so design and so correlate such device with a door or window and to so attach the device to the frame work of such door or window, as to assure a perfectly tight union between all these parts, when the door or window is closed.

Another important object of this invention is to construct the major parts of the device in the shape of standardized units, having uniform cross-sections, portions of which latter being adapted to form interengageable, continuous elements, designed to extend over the entire length of the device and to form a water-tight connection with one another.

A further object of this invention is to provide in such a device a hollow, stationary member, designed for and having the general purpose of forming a channel or trough, and a movable member operatively connected with the former, the connection between the two members forming a continuous hinge, uninterrupted over the entire length of the device; said stationary member being so constructed as to provide a seat for said movable member, adapted to unobtrusively accommodate the latter member, when in inoperative or swung-down position.

A further object of this invention is to provide in a device of this kind a stationary member, adapted to be either attachable to the framework of doors or windows, or form itself a part of the frame work, and having provisions for concealing and making unobtrusive

its means of attachment, thereby eliminating any possibility of contact with the latter.

A still other object of this invention is to provide the movable member of such device with integral or otherwise intimately associated operating means, adapted to facilitate the movement of said member to either an elevated, swung-out, or an inoperative, seating position, relative to its stationary member.

Another object of this invention is to provide in cooperation with my device a door or window provided with grooved edges adapted to facilitate the operation of the movable member therewithin, and to form a water and weather-tight seal with said member when the latter is in its operative position, while the door or window is closed.

A still further object of this invention is to provide in a device of this kind, means for forcibly holding the movable member in either operative or inoperative position, and for providing a weather and water-tight contact between between said member and a door or window edge engaged by the latter.

Still another object of my invention is to provide, in cooperation with my device, reinforced door or window mountings provided with recesses adapted to be engaged by the movable member of my device, and further adapted to facilitate the operation of said member when the door or window is being either closed or opened.

The foregoing and still other objects of this invention will become more readily evident as the following description progresses, and from the hereinafter explained drawing of the various forms of my device, which drawing, while showing a number of different designs, is by no means to be construed as limiting my invention to the illustrations only, and in which

Fig. 1 is plan view of one of the forms of my device, as connected with a frame and a door or window, the latter shown open.

Fig. 2 is a partial elevation of my device in a position assumed when the door or window is closed.

Fig. 3 illustrates a cross-sectional elevation of a spring-operated form of my invention.

Fig. 4 is an end view of a modified form of my device embedded in a frame work.

Fig. 5 illustrates a reinforced edge structure of a door or window with another form of my device in inoperative position.

Figs. 6 and 7 show different types of my device adapted for thresholds, and

Fig. 8 is a modified form of the edge groove,

and a portion of my device in engagement with an internal, resilient weather-proofing element disposed within the edge groove.

Referring now more specifically to the illustrations, in Fig. 1 there will be observed a frame for a door or window, consisting of a cross member 10, disposed between two oppositely arranged side members or uprights 11 and 12, both provided with recesses 13 and 14 forming door or

10 window jambs. Hinged to member 12 at 15 is a door or window 16, shown in swung-out position in Fig. 1 and closed in Fig. 2. Secured to cross member 10 and extending with its ends into

15 uprights 11 and 12, is my weather-proofing device (seen in end-view in Fig. 2), and comprising a base member 17, having a generally channel-shaped cross section forming a trough over the entire length of the structure, and a movable member 18, which is operatively at 19 connected with the base member. The connection

20 between the two members constitutes an uninterrupted, continuous hinge structure consisting of a substantially round bead 20 and a rounded channel 21, the latter embracing said bead over

25 more than half of its engageable surface. Both the bead and the channel form integral parts of their respective members 17 and 18, and extend over the entire length of the device.

The attachment of the base member is prefer-

30 ably accomplished from within in trough 22, in which countersunk holes 23 are provided for receiving the heads of bolts or screws. The operation of movable member 18 is preferably accom-

35 plished by providing therewith an integral or otherwise intimately united abutment 24, which extends into the path of the outer end of the door or window. At the lower corner, and ex-

30 tending from the weather face of the door or window, there will be seen an actuating abut-

40 ment 25, which latter is adapted to contact with abutment 24 of the movable member, when the door or window reaches its closing position. During the final closing movement of the door or window, abutment 24 is forced to swing out-

45 wards, thereby causing movable member 18 to swing upwards and into the edge recess 26, provided in the material of the door or window.

When in its uppermost position, member 18

50 contacts with its outer surface, the slanting part 27 of the recess, and forms therewith a water and weather-proof joint. When the door or window is being opened, the lowermost outer edge of the recess passes over member 18 and causes it to move gradually downwards to its

55 normal, closing position, as abutment 25 releases abutment 24 of the movable member. Stationary or base member 17 is provided with a generous seat 28 for securely supporting movable member 18 at its outer portion. The edge of

60 the latter is either inclined, as shown, or may be straight, but in any event it forms a fairly tight contact with the corresponding recess provided in the stationary member. The latter

65 possesses interior and exterior approaches 29 and 30, the edges of which may either lay flat over the cross member of the frame or may be embedded therein, as illustrated in Fig. 2 at

70 31. The base member may also completely substitute cross member 10 of the frame work, in which case it is directly attached to the floor and is united with opposite side frame members

75 11 and 12.

Particular attention is directed to the placement of abutment 24 of the movable member.

75 Not only is this abutment arranged at that end

of member 18 which is directly under the outer or closing edge of the door or window, but it is adapted to be completely weather-proofed and to operate in a specially formed recess 32 in upright 11, as indicated in Fig. 1.

The channel-shaped or trough portion 22 of base member 17 is intended for absorbing and conveying moisture from within the structure to without, as will be presently explained in connection with other figures, when movable member 18 is in its swung-up or operative position, as illustrated in Fig. 2. Normally, however, member 18 engages seat 28 of the stationary member 17, and forms with the latter either a threshold for doors, or a sill for windows, in the manner shown in Fig. 2. It is to be noted that when member 18 is in its inoperative position, the entire device is bare of any crevices, projections or other obstructions, and presents a smooth, unobtrusive structure, capable of being used with such complete safety as present-day solid thresholds and sills. It will be also evident from the drawing that the present invention eliminates any possibility of accumulating dirt, dust, rug fiber or small obstructions such as matches, toothpicks and the like, all of which may in some way impair the proper operation for which the device is intended.

In the modified form of the device, shown in Fig. 3, additional features are incorporated for improving its functions, while both in normal and in its operative position. In this figure, numeral 32 denotes the base or stationary member having outer and inner approaches 33 and 34, and a substantially round, stationary hinge element 35. At the upper end of approach 34 there is provided a seat 36 for the movable member. Between the seat and hinge element 35 the base member forms a trough, having a drain outlet 37, indicated in broken lines. Countersunk holes 38 located in the bottom of the trough are intended for the reception of attaching means.

The movable member 39, shown in its normal position in full lines, engages with its outer, 45 swinging end the seat 36 of the base member. Attention is called to the close fit between the edge of the movable member and the inclined step adjacent to seat 36, as indicated at 40.

The portion of member 39 engaging hinge element 35 comprises a correspondingly rounded shape 41, which embraces that element over more than half of its engageable surface. Both hinge elements 35 and 41 of the two members are integral with the latter and extend over their entire length.

Element 41 is built out into a lug 42, to which is hinged the head 43 of guide pin 44, the free end of which latter is operatively mounted in bracket 45, secured within the trough of the base member. Supported by the pin is a washer 46 and a spring 47, the latter adapted to exert pressure against head 43 and the washer. This entire arrangement, concealed within the trough, forms a toggle joint structure, actuated by and holding the movable member constantly under positive tension, while that member is either in its operative or inoperative position, and at the same time improving the functions of the member either in contact with a door or window, or when serving with the base member as threshold or sill.

At one end of the movable member there is provided an operating lug or abutment 48, which is adapted to be engaged by a corresponding

actuating abutment 49 secured to the outer and lower edge of a door or window when the latter is brought to its closing position. In this construction the operation of the movable member, and the cooperation of the two abutments is somewhat different from the modus operandi explained in connection with Figures 1 and 2. While in the latter case door abutment 25 engages and remains in engagement with member 0 abutment 24, in order to maintain movable member 18 in its elevated position and in tight contact with surface 27 of door groove 28, the operating and tightening functions in the design of Fig. 3 are performed mostly by the toggle joint. It will be noted that actuating abutment 49 forms a corner, the lower leg 50 of which being intended to engage operating member 39 when the latter is in its elevated position, shown in broken lines, and to move said member downwards when the door or window is being opened.

Due to the construction and operation of the toggle joint, the function of the movable member, during the closing movement of the door or window, is first delayed, whereafter follows a rapid elevation of that member. As abutment 49 engages abutment 48, when the latter is in its full-line, upright position indicated by radial line I, and is moved towards centre line II, member 39 is gradually elevated, and its hinge element with lug 42 is turned, whereby spring 47 is caused to be compressed. The moment abutment 48 reaches and even slightly passes centre line II, spring 47 will cause abutment 48 to snap to its extreme position, indicated by line III, while at the same time member 39 becomes elevated to its broken-line position, in which it is forcibly kept in contact with the inclined surface 51 of the edge groove formed in the door or window. The spring force moving member 39 upwards also is instrumental in closing and pushing the door or window against its jamb stops.

As the door or window is being opened, bottom leg 50 of abutment 49 moves swung-up member 39 in downward direction, and when the latter reaches a position at which abutment 48 passes centre line II, the toggle arrangement completes the downward movement of member 39, and retains it in contact with seat 36 under tension. Such forcible retention of the movable member in its normal, closed position prevents it from being accidentally elevated while the door or window is open, which feature enhances the safety of the device when in use, and prevents foreign matter from entering the inclined abutting joint 40 between the stationary and the movable member.

In Figure 4 is illustrated a construction of my device intended to be embedded in the floor or frame structure, and comprises a trough-shaped base member 52 provided with a drain 53 and a channel-formed hinge element 54 embracing a round hinge element 55 of movable member 56. An added feature of this construction consists of an auxiliary weather-proofing element 57 which is intended to engage the outer edge of member 56. This weather-proofing element consists of a resilient member, arranged over the entire length of edge groove 58 of the window or door 59, and possesses at its upper end a resilient cushion 60 adapted to contact with inclined face of member 56. As the latter is moved up, it compresses the element towards the curved 75 face of groove 58, until it reaches its dotted-

line position, at which the element is allowed to swing downwards into engagement with the movable member. Due to its construction the element holds that member under tension and forms a weathertight joint with the latter. When the door or window is being opened, movable member 56 presses element 57 out of its way until it reaches the normal closing position shown in full lines.

A construction similar to that just described is illustrated in Fig. 8, in which an auxiliary weather-proofing element 60 is provided in a specially designed recess 61. The function of element 60 resides in forcibly engaging movable member 62, and pressing it against a resilient cushion 63, which forms a part of reinforcing member 64, embracing the exterior edge 65 of a door or window. This reinforcing member also serves at its outer surface as actuating abutment for elevating moveable member 62 of the 20 device.

In the modification illustrated in Fig. 5, movable member 66 is provided with longitudinal grooves 67 adapted to contact with resilient ribs 68 extending from the inclined surface 69 of a hollow metal edge construction 70 secured to door or window 71. This metal edge has for its purpose to not only do away with the weakening of the door or window edge, due to the formation of the groove therein for accommodating the movable member of my device, but is intended to be exchangeable, adjustable and to serve as "kick plate" for the door. Incidentally, its groove may be fashioned more accurately and the whole structure is more substantial and capable of withstanding harder usage and abuse.

The modified forms in Figures 6 and 7 are intended to demonstrate that it is possible to accomplish the desired results in my device by employing different designs of cross-sections. Thus in Fig. 6 a continuous, hollow shape of extruded metal is selected for the stationary base member 72, in which the hinge element 73 forms a rounded channel extending into a large seat 74. The latter is perforated at 75 to allow water to enter the hollow interior of the member, from which it may be drained by a weep-hole 76 or pipe 76'. The movable member 77 possesses a solid, rounded, hinge element 78 which is embraced by element 73 of the base member. The attachment of the base member is accomplished by the employment of screws or other fastening means adapted to pass through countersunk opening 79 of seat 75 and apertures 80 provided in the supporting plate of the base member.

In Figure 7 base member 81 possesses compartment 82 under weather side approach 83, and at the bottom there is provided a drain opening 84 for conveying moisture from the structure when movable member 85 is in its operative position. A broad seat 86 is formed in the base member for supporting the movable member in its normal, downward position. A countersunk hole 87 indicates the manner of attachment of this modified structure. The hinge element 88 of the base member extends sideways from upright portion 89, and its connecting portion may be perforated if desired, as indicated at 90. The hollow hinge element 91 of the movable member embraces hinge element 88 in the usual manner.

In the foregoing, various shapes, constructions and working arrangements of my device were 75

described, in order to bring out the important facts that this invention is capable of a great many modifications and modes of operation. Both the base and movable members are in-

- 5 tended to be made from extruded metal of the same kind, as for instance, brass, but may be produced of different materials and in any desired combination. In any event the members are to be designed to form a solid, closed structure when in their normal use, at which they serve as threshold or sill when the door or window is open, and to constitute a drainable trough when in operative position, while the door or window is closed.
- 10 15 20 25 30 35 40 45 50 55 60 65 70 75
- 15 The connection between the two members is continuous and invisible and consists of only two elements forming integral parts of the members, adapted to engage one another and to be slipped one over the other endwise. Inasmuch as the movable and base members are uninterrupted over their entire length, as are their hinged inter-connections, they form an absolutely weather-tight structure in themselves. When the movable member is in its operative position and in engagement with the groove provided at the edge of a door or window, the device is intended to form a weather-tight connection with the latter. If, by any chance, water should penetrate and pass the swung-up movable member, the trough formed in the stationary member is designed to absorb and to facilitate conveying moisture to without the structure.

In addition to the aforesaid features, the device is so constructed as to provide a generous support for the movable member, when the latter engages the base member and to form close contact between the registering edges of the two members, so as to exclude any possible chance for dirt or other foreign matter entering between and affecting the correct cooperation between the two members.

An important factor of my invention is the attachment of the device to existing door or window frames, so as to prevent entrance of moisture at the ends of the structure, attention is being called to the typical installation shown in Fig. 1 illustrating that the ends of the device are completely embedded in the framework. All of the above advantages apply equally to both the illustrated designs as well as to the many possible modified forms my device is capable of assuming, and while I have shown specific constructions of my invention, it is quite obvious that the latter may be improved upon and its construction changed to suit various conditions arising from its intended application, and I therefore desire to protect my right to make such changes and improvements, all within the broad scope of the annexed claims.

I claim:

1. In a weather-proofing device, two operatively connected members, one being stationary and provided with approaches along both of its edges, the other being movable relative to the stationary member, their operative connection comprising a continuous hinge structure formed by an uninterrupted, substantially round bead and a hollow, uninterrupted extension embracing said bead over more than half of its roundness, said connection extending over the entire length of both members and forming the top edge of one of the approaches.
- 65 70 75
2. In a weather-proofing device, two operatively connected, continuous members made of

extruded material, the cross-section of each member being uniform over its entire length, the connection between the two members being substantially hinge-like and extending uninterruptedly over the entire length of the members their connecting portions forming integral parts of the respective members and being so located as to constitute a weather-proof top edge of one of the approaches of the device.

3. The combination with a frame work of doors or windows, of a weather-proofing device extending between two oppositely disposed frame members and adapted to cooperate with the corresponding edge of a door or window, operatively associated with the two frame members, said device extending into the material of the two frame members and comprising a hollow, substantially channel-shaped stationary member, having two approaches and a movable member, each member having a predetermined cross-section, uniform over the entire length thereof, a hinge-like structure, forming the top portion of the approaches operatively connecting said members and comprising a substantially round bead forming an integral part of one of the members, and a correspondingly rounded groove, being an integral part of the other member, and embracing said bead over more than half of its surface, both bead and groove being continuous and uninterrupted and extending over the entire length of said members, said movable member adapted to normally contact with and stay in unobtrusive position relative to said stationary member when said door or window is open, and to swing into weather-proof engagement with the corresponding edge of the door or window when the latter is closed.

4. In a device as set forth in claim 3, said corresponding edge of the door or window provided with a recess extending over the entire length of that edge and adapted to accommodate said movable member when the latter is in its swung-up position.

5. In a device as set forth in claim 3, said movable member provided with an extending abutment adapted to be normally disposed in the path of said door or window, a corresponding abutment provided with the latter and adapted to engage the first mentioned abutment when the door or window closes, said corresponding edge of the door or window provided over its entire length with a recess adapted to facilitate the operation of said movable member therewith and to accommodate and form a weather and water-tight connection with said movable member when the latter is in its swung-up position, said extending abutment of the movable member forming an exterior part of the latter and adapted, when operated by said door or window abutment, to swing up said movable member into contact with the groove of the door or window edge.

6. The combination with a frame work having operatively suspended doors or windows, of a weather-proofing device extending over one frame member and embedded into two oppositely disposed frame members, the edge of the door or window, corresponding to said one frame member provided with a recess over the entire length of that edge, said device comprising a substantially channel-shaped, stationary member, having two approaches and adapted to drain moisture from within the device, and a movable member operatively connected with said stationary member, both members having a predeter-

mined cross-section which is uniform over their entire length, the connection between the two members constituting a continuous waterproof hinge, located at and constituting the top portion of one of the approaches and extending over the entire length of both members, said hinge forming integral parts of said members and comprising a substantially round bead provided with one member and a correspondingly rounded channel provided with the other member and partially embracing said bead, both the bead and said channel being uninterrupted, and constituting a reinforcement and support for the movable member over its entire length, the movable member adapted to normally register with and remain unobtrusive within said stationary member when the door or window is open, and to swing into operative position and to engage the recess formed at the edge of the door or window when the latter is closed, and actuating means provided with said movable member and said door or window for causing that member to swing into its operative position when the door or window closes.

7. In a device of the class described, adapted to extend into the material of two oppositely disposed parts of a door or window frame and further adapted to cooperate with a door or window mounted in such frame, a stationary member having two approaches secured to the frame portion connecting said oppositely disposed frame parts and having a predetermined cross-section which is uniform and is made of one piece of material over the entire length of the member, portions of said member constituting substantially a channel formation adapted for absorbing and draining water, a movable member operatively connected with said stationary member, having a predetermined uniform cross-section and made of one continuous piece of material, the connection between the two members resembling a hinge, located at the top and constituting a smooth, upper edge of one of the approaches and forming a dirt-proof connection of the upper structure of the device, each component part of the hinge forming an integral, uninterrupted portion of one of the members, said hinge parts interlocking with one another over the entire length of said members, the movable member adapted to normally rest against a seat provided with the stationary member, when the door or window is open, and to swing away from that seat when operated, the edge of the door or window facing the device being provided with a recess over its entire length for facilitating the operation within, and for accommodating and contacting with said member, when the latter is in its operative, swung-out position, operating means extending from said movable member, actuating means for said operating means provided with the door or window and adapted to engage said operating means just prior to closing the door or window.

8. In a device of the class described, as set forth in claim 7, said operating means forming a part of said movable member and comprising an abutment arranged in the path of the door or window, said actuating means comprising an abutment arranged without and extending from the door or window, said operating means being concealed within one of the frame parts and arranged at one end of said movable member.

9. In a device of the class described, as set forth in claim 7, said operating means forming an integral portion and located at one end of

said movable member and being concealed within one of the frame parts, a spring-induced toggle arrangement engaging said movable member and adapted to hold it under tension while in either operative or inoperative position, and to facilitate the instantaneous operation of the movable member when the door or window is being either closed or opened.

10. The combination with a door or window and a frame work therefor, the door or window provided with recesses at its edges, of a device for the purpose described comprising stationary and movable members interhinged with one another over their entire length, said stationary member provided with two approaches, the interhinged portions of the members forming integral parts of the structures of said members, and constituting a weather-tight connection between the members, and located at the top, and forming a rounded, unobtrusive, dirt-proof upper edge of one of the approaches, spring controlled operating means for said movable member forming a part of the latter, actuating means associated with the exterior face of the door or window and adapted to engage said operating means, when said door or window is being closed, the recessed edges of the door or window adapted to be engaged by and to facilitate the operation of said movable member therewithin, and to form a weather and water-tight connection between one of its portions and the movable member engaging it, and means provided with said device for tensionally holding said movable member in operative position and for improving its weather-excluding contact with said portion of the recess.

11. The combination, as set forth in claim 10, said recess provided with means for engaging said movable member in order to enhance the weather-proof contact between the latter and the recess.

12. In a weather-proofing device for, and in cooperation with doors or windows, a stationary member, provided with approaches at both of its sides, a movable member operatively associated with the former over its entire length, said members provided with means for absorbing and draining moisture outwards and from within the structure of these members, said stationary member provided with means for facilitating its unobtrusive, and concealed attachment to a frame work for doors or windows, seating means for said movable member arranged in said stationary member, the operative connection between the two members being weather-proof and consisting of continuous, uninterrupted, inter-engaged hinge elements, constituting the upper edge of one of the approaches and forming integral parts of said members and adapted to be slipped over one another, operating means provided with and constituting an integral portion of said movable member, said latter member adapted to normally contact and form a dirt-proof connection with said seating means of the stationary member when the door or window is open, the edges of the door or window provided with a recess-forming reinforcement, adapted to cooperate, and to form a weather-tight contact with said movable member when the door or window is closed, means associated with the door or window for actuating said operating means of the movable member when the door or window is caused to close.

13. A weather-proof threshold or sill comprising a stationary member, having approaches at

- both of its sides, a movable member hinged therewith over its entire length, the hinge connection between the two members forming the top edge of one of the approaches and being 5 weather-proof and consisting of interlocking elements forming integral portions of said members, the major structure of said stationary member being substantially channel-shaped for the purpose of draining moisture therefrom.
- 10 14. In a weather-proofing device, extruded metal members, one being hollow and stationary, and provided with approaches at both of its edges, the other being movable, both members inter-connected with one another by means of 15 a weather-tight hinge structure extending over their entire length and consisting of interlocking hinge elements forming integral parts of the members, said hinge-structure forming the top portion of one of the approaches of the stationary member.
15. In a weather-proofing device, extruded metal members, one being hollow and stationary, and provided with approaches at both of its edges the other being movable, both members inter-connected with one another by means of a weather-tight hinge structure extending over their entire length and consisting of interlocking hinge elements forming integral parts of the 10 members, said stationary member forming a trough, adapted to accommodate water when said movable member is elevated, both members adapted to form a threshold or sill when said movable member is in inoperative position, said 15 hinge structure constituting the top portion of one of the approaches of the threshold.

JOSEPH F. FAUNER.
